WARE.

DRIVING MECHANISM FOR WASHING-MACHINES.

1,147,406.

Specification of Letters Patent.

Patented July 20, 1915.

Original application filed March 4, 1907, Serial No. 360,400. Divided and this application filed February 10, 1910. Serial No. 543,105.

To all whom it may concern:

Be it known that we, HENRY S. JUDD and HENRY PLETSCH, citizens of the United States, residing at Chicago, in the county 5 of Cook and State of Illinois, have invented certain new and useful Improvements in Driving Mechanism for Washing-Machines, of which the following is a specification.

The present invention relates to improvements in driving mechanism for washing machines and seeks to provide a simple and efficient drive mechanism for actuating washing machine tubs that are arranged to oscillate upon a horizontal axis below the 15 center of gravity.

The present application is a continuation in part of an earlier application filed by us March 4, 1907, Serial No. 360,400.

The invention consists in the features of 20 improvement hereinafter set forth, illustrated in the preferred form in the accompanying drawings and more particularly pointed out in the appended claims.

In the drawings, Figure 1 is an end elevation with parts broken away; Fig. 2, a section on the line 2—2 of Fig. 1; Fig. 3, a detail of a modification.

Like parts are indicated by the same letters in all the figures.

30 The tub A has the rigid end pieces A¹ provided with the lining panels A² to which is attached the sheet A³, making up the sides, bottom and part of the top of the tub. The sheet A³ overlaps the crimped edges A⁴ of the panels A² and is held upon the ends A¹ by means of the screws A⁵.

The frame B which rests upon the ends A¹ and is riveted at the sides to the sheet A³, is provided with the downwardly depending L-shaped flange B² having therein the packing B³. The door B⁴ having the downwardly depending flanges B⁵ adapted to engage the packing B³ is held in the tub by means of the screws B⁶ adjustably mounted in the lever B⁷ and riding upon the tapered lugs B⁸ upon the door. The lever B⁷ is held by means of the screw B⁹ and the lug B¹⁰ upon the body of the tub.

50 The plates C having the inwardly-turned bottom flange C¹ are held by means of the bolts C² to the end pieces A¹ and are provided with the trunnion C³ and shaft C⁴

which bear upon the brackets C⁵ upon the frame C⁶. The plate D which is mounted upon the shaft C⁴ has therein the arc-shaped slot D¹ within which travels the lug D² rigidly attached to the plate C. The springs D³, D⁴, are attached by means of the lever D⁵ to the plate D at one end and at the other are connected by means of the bolt D⁶, 60 the knife edge D⁷, nut D⁸ and lug D⁹ to the frame C⁶. The driving spring E is attached at one end to the tub by means of the bolt E¹ and knife edge E² and at the other end to the lever E³ which is rotatably mounted 65 upon the shaft C⁴. The knife edge E² bears upon the upper surface of the laterally projecting part e⁴ of a bracket E⁴ that is suitably bolted to the end wall of the tub, and the bolt E¹ is shown as passing through the 70 laterally projecting part of the bracket E⁴ and through the knife edge E². The lever E³ is connected by means of the rod G to the crank G¹ which is mounted upon the shaft G² and driven by means of the belt 75 G³ and pulley G⁴. The spring D⁴ is attached at one end to the lever D⁵ and has at the other end the plug H slidably mounted within which, is the rod H¹ having at its end the head H² adapted to engage the 80 plug H.

Referring to Fig. 3, the spring J incloses the spring J¹ and has at one end the plug J² which engages both the inner and outer springs. At the other end the plug J³ engages the spring J and is rigidly attached to the bolt J⁴. The plug J⁵ engages the spring J¹ and is held slidably mounted upon the bolt J⁴ and adapted to engage the head J⁶ upon such bolt. 90

The spring illustrated in Fig. 3 may be used as a substitute for the springs shown in Figs. 1 and 2 if such arrangement should seem desirable.

It will be evident that although we have 95 shown in our drawings an operative structure, still numerous changes could be made in the shape, size and arrangement of parts without departing materially from the spirit of our invention. The springs might 100 be interchanged and numerous other changes might be made.

The use and operation of our invention are as follows:—We provide a tub which os-

cillates about an axis below the center of gravity, said axis relatively near the bottom of the tub. The shape of the tub is such that as oscillation takes place, the water 5 therein describes a path essentially different from that of the tub. In other words, the water in the tub is reflected from surface to surface as the tub oscillates. The tub is made up of rigid ends preferably of wood 10 having metallic linings partially overlapping the wood with a metallic side sheet completely surrounding the edges of the wooden ends and soldered to the end linings. By this arrangement we are enabled to nail or 15 screw the metal part to the wooden part of the tub without interfering with the soldered connection of the metal parts. It should be noted that the driving spring E is interposed between the lever E³ which extends 20 upwardly from its pivot, and the tub, and in the preferred embodiment of the invention set forth, the axis of the pivot of the lever coincides with that of the tub and the spring extends between the upper end of the lever 25 and the upper portion of the tub. This arrangement allows the tub to oscillate through a larger arc than the lever, without placing undue tension on the driving spring. In the preferred embodiment shown, the in- 30 clin retracting springs are connected to a pivot plate on the axis of the tub and the latter provided with a pin which reengages an arc-shaped slot in the pivot plate. By this means the tub has a certain free gravity 35 fall independent of the springs. This fall continues until the lug is carried around to the end of the slot whereupon the retracting springs come into play. This is provided so that when the tub is running light it will 40 still be enabled to get sufficient momentum in each stroke to do the necessary work without undue jar and strain upon the driving mechanism. Thus, as the tub is started the connecting rod throws the driving lever 45 out of line between the point of application on the tub and the axis, thus exerting tension upon the driving spring. In the devices where the springs tend at all times to maintain the tub central, the driving mechanism 50 must immediately commence work against these retracting springs. In this device, however, the driving mechanism is not called upon to overcome the tension of the springs at the start of the stroke where the mecha- 55 cal advantage is least. We have shown auxiliary checking springs; that is to say, in one case three springs, two of which are constantly operative, a third operative merely when the elongation of the other two has 60 reached a certain point. We have shown also springs one within the other wherein the outer spring is stretched until the head on the rod engages a plug in the inner checking spring to put it to work. This second- 65 ary spring may be termed a checking

spring since it becomes active only toward the end of the stroke and tends to prevent and reversing the tub with a minimum of a too great travel, at the same time stopping jar and resulting strain on the mechanism. 70

We claim:—

1. Driving means for a washing tub comprising a frame having suitable bearings, trunnions projecting laterally from said tub near the bottom thereof and supported by 75 said bearings, a lever pivotally mounted upon one of said trunnions and extending upwardly therefrom, a driving rod connected to said lever and a driving spring connected at its lower end to the upper portion of said 80 lever and extending upwardly therefrom, said spring being connected at its upper end to the tub.

2. Driving means for a washing tub comprising a frame having suitable bearings, 85 trunnions projecting laterally from said tub near the bottom thereof and supported by said bearings, a lever pivotally mounted upon one of said trunnions and extending upwardly therefrom; a driving rod connect- 90 ed to the upper portion of said lever, a driving spring connected at its lower end to the upper portion of said lever, a bracket connected to the upper portion of the tub and having a laterally projecting part, a 95 knife-edge bearing upon the laterally projecting part of said bracket, and a rod passing through said laterally projecting portion of the bracket and connected to said knife- edge, the lower end of said rod being ad- 100 justably connected to the upper end of said driving spring.

3. Driving means for a washing tub comprising a frame having suitable bearings, 105 trunnions projecting laterally from said tub near the bottom thereof and supported by said bearings, a lever mounted for oscillatory movements about a horizontal axis and extending upwardly therefrom, a driving rod connected to the upper portion of said 110 lever, and a driving spring connected at its lower end to the upper portion of said lever and extending upwardly therefrom, said spring being connected at its upper end to the tub. 115

4. Driving means for washing tubs, comprising a frame on which the tub is mounted so as to oscillate about a fixed horizontal axis near the bottom thereof, a plate rotatably mounted about said axis, said plate provided with an arc-shaped slot therein, a lug rigidly attached to the tub adapted to engage in said slot, a plurality of retracting springs attached at their one end to the frame and at their other end to the said 120 plate, and means to impart an oscillatory motion to the tub.

5. Driving means for washing tubs, comprising a frame on which the tub is mounted so as to oscillate about a fixed horizontal 125 axis near the bottom thereof, a plate rotatably mounted about said axis, said plate provided with an arc-shaped slot therein, a lug rigidly attached to the tub adapted to engage in said slot, a plurality of retracting springs attached at their one end to the frame and at their other end to the said 130 plate, and means to impart an oscillatory motion to the tub.

axis near the bottom thereof, a lever rotatably mounted about said axis, a spring attached to the tub at one end and to said lever at the other end, a plate rotatably mounted about the horizontal axis, said plate provided with an arc-shaped slot therein, a lug rigidly attached to the tub adapted to engage in said slot, and a plurality of retracting springs attached at one end to the frame and at the other end to said plate.

6. Driving means for washing tubs, comprising a frame on which the tub is mounted so as to oscillate about a fixed horizontal axis near the bottom thereof, a triangular plate rotatably mounted at its apex about said axis, a slotted connection between said plate and tub, retracting springs attached at one end to the frame and at the other end to the two remaining apexes of the plate, and means to impart an oscillatory motion to the tub.

7. Driving means for washing tubs, comprising a frame on which the tub is mounted so as to oscillate about a fixed horizontal axis near the bottom thereof, a plate rotatably mounted about such axis, a slotted connection between said tub and plate, levers pivoted to said plate, and a retracting member for the tub comprising a plurality of springs connected at one end to the frame and at the other end to said levers, and

means to impart an oscillatory motion to the tub.

8. In a machine of the character set forth, the combination of a frame, a body pivoted thereon to oscillate about a horizontal axis below its center of gravity, a lever pivotally mounted to oscillate about an axis coinciding with the axis of said body, said lever extending upwardly from its axis, a spring connected at its lower end to the upper portion of said lever and extending upwardly therefrom, said spring being connected at its upper end to said body, a driving rod connected to said lever, and retracting springs connected to said body for reversing the movement thereof.

9. In a machine of the character set forth, the combination of a frame, a body pivoted thereon to oscillate about a horizontal axis below said center of gravity, retracting springs connected to said body to reverse the movements thereof, a lever mounted to oscillate about a horizontal axis and extending upwardly therefrom, a driving rod connected to said lever, and a driving spring connection between said lever and said body.
